UNITED STATES PATENT OFFICE

SAMUEL A. STRZELCZYK, OF MILWAUKEE, WISCONSIN

DRAFTING TABLET

Application filed July 9, 1928. Serial No. 291,455.

This invention relates to drafting tablets. Objects of this invention are to provide a novel form of drafting table, which is so constructed that a plurality of straight edges, or 5 rulers, are provided which are adapted to be moved either longitudinally of the tablet, or transversely thereof, and which are provided with graduations so that the utmost speed and ease may be obtained in laying out 10 sketches or other drawings.

Further objects are to provide a novel form of drafting tablet, in which the paper is fed from a roll carried in a housing adjacent the upper end of the tablet, and the paper passes 15 below stationary guides and may be withdrawn from the bottom of the table and torn off against the lowest stationary guide.

Further objects are to provide a drafting table which is of extremely simple construction, which may be readily produced, and which is practical in operation.

An embodiment of the invention is shown in the accompanying drawings, in which:

Figure 1 is a plan view of the tablet with 25 portions broken away.

Figure 2 is a longitudinal sectional view on the line 2—2 of Figure 1.

Figure 3 is a transverse sectional view on the line 3—3 of Figure 1.

Referring to the drawings, it will be seen that the tablet is composed of a base plate 1, which has projecting marginal flanges 2 (see Figure 3). At the lower end of the tablet a 35 transverse, stationary guide 3 is provided and has its ends bent over the marginal flanges 2, one of the ends being indicated by reference character 4. It will be seen that this stationary guide has a portion which passes over the projecting edge of the marginal flange inset within the said flange, as indicated by reference character 5. This is to prevent the fixed guide 3 from slipping. The 40 guide is graduated, as indicated.

A similar upper fixed guide 6 is also provided adjacent the upper end of the tablet. Between these guides a slideable rule 7, also provided with graduations, is provided and has its ends turned over and guided by the 45 guides 3 and 6, as most clearly shown in Figure 2. It is apparent that this rule may be

set at any desired distance from the margins of the paper sheet 16, which is carried beneath the guides 3 and 6. Further, any desired vertical measurement may be laid off along the rule 7 and a corresponding line drawn. Further than this, a slideable, transverse rule 8 is provided and has its ends folded over the marginal flanges 2 of the base plate, as indicated in Figure 3. This horizontal rule may be slid to any position and the appropriate 60 distance laid off and the lines drawn as required in the sketch.

The paper sheet 16 is fed from roll 16'. This roll is carried by a central rod 9 which is journaled in the vertical plates 10 and 11. 65 The vertical plate 10 has its bottom edge flanged and bent over the marginal guide 2, as indicated in Figure 1 by the reference character 12. The vertical plate is integral with the horizontal plate or cover 13 which 70 extends across the top of the roll and is provided with a keyhole type of slot 14 adjacent its free end. This keyhole type of slot receives the hook-like end 15 projecting upwardly from the vertical plate 11. The vertical plate is similarly provided with a portion flanged over the appropriate marginal edge 2 in a manner identically similar to that 75 previously described.

Thus, when it is desired to renew the roll, 80 all that is necessary is to spring the hook-like end 15 inwardly into the enlargement of the keyhole slot 14, and thereafter swing the cover upwardly to a slight distance. The 85 end plates 10 and 11 may be sprung apart sufficiently to allow the removal of the used roll and the replacement of a new roll.

It will be seen that a very compact, self-contained, and simple type of drafting tablet is provided by this invention. It will be seen 90 further that the tablet may be very readily used to lay out sketches, plans, or any other drawing required, and that the measurements are carried by the sliding rules which are for the horizontal and vertical lines, and also are 95 carried by the stationary upper and lower guides. Thus the utmost ease in sketching and drawing is afforded by this tablet.

Although the invention has been described in considerable detail, such description is in 100

tended as illustrative rather than limiting as the invention may be variously embodied and as the scope of such invention is to be determined as claimed.

- 5 The paper sheet 16 is fed from roll 16'. This roll is carried by a central rod 9 which is journaled in the vertical plates 10 and 11. The vertical plate 10 has its bottom edge flanged and bent over the marginal guide 2, 10 as indicated in Figure 1 by the reference character 12. The vertical plate is integral with the horizontal plate or cover 13 which extends across the top of the roll and is provided with a keyhole type of slot 14 adjacent 15 its free end. This keyhole type of slot receives the hook-like end 15 projecting upwardly from the vertical plate 11. The vertical plate is similarly provided with a portion flanged over the appropriate marginal 20 edge 2 in a manner identically similar to that previously described.

Thus, when it is desired to renew the roll, all that is necessary is to spring the hook-like end 15 inwardly into the enlargement of the 25 keyhole slot 14, and thereafter swing the cover upwardly to a slight distance. The end plates 10 and 11 may be sprung apart sufficiently to allow the removal of the used roll and the replacement of a new roll.

30 If desired a cutout 17 may be made in the bottom edge of the base plate so that the paper may be easily grasped in withdrawing it.

It will be seen that a very compact, self-contained, and simple type of drafting tablet 35 is provided by this invention. It will be seen further that the tablet may be very readily used to lay out sketches, plans, or any other drawing required, and that the measurements are carried by the sliding rules which 40 are for the horizontal and vertical lines, and also are carried by the stationary upper and lower guides. Thus the utmost ease in sketching and drawing is afforded by this tablet.

45 Although the invention has been described in considerable detail, such description is intended as illustrative rather than limiting as the invention may be variously embodied and as the scope of such invention is to be determined as claimed.

I claim:—

50 A drafting tablet comprising a base plate having laterally projecting marginal flanges along its longitudinal edges, a pair of spaced 55 graduated guides having their ends folded over the said flanges with a portion thereof set into said flanges, said guides being spaced upwardly a slight distance from the base plate to receive a sheet of paper between the 60 guides and the base plate, a transverse graduated rule mounted upon the base plate between the spaced guides and having its ends slidably engaged with the marginal flanges of the base, and a longitudinally extending 65 graduated rule mounted upon the base with

its ends slidably engaging the spaced guides and traversing the transverse graduated rule whereby the longitudinal graduated rule may be moved over the plate and cooperate with the graduated guides as well as the transverse rule, the base plate having a notch at one end thereof extending beneath one of the spaced guides whereby a sheet of paper beneath the guide may be engaged by the operator to move the same beneath the guide.

70 In testimony that I claim the foregoing I have hereunto set my hand at Milwaukee, in the county of Milwaukee and State of Wisconsin.
